HEADING AND LIKE MACHINE

Alexander Basil Watt, Handsworth, Birmingham, England, assignor to G. K. N. Group Services Limited, Smethwick, England, a British company

Application June 19, 1952, Serial No. 294,434

6 Claims. (Cl. 10—12.5)

1

This invention relates to heading and like machines of the kind having a body in the face of which is an opening containing a die into which the work is fed, and a reciprocating ram having a head upon which is mounted a movable punch carrier carrying two spaced punches, the carrier being movable transversely to the movement of the ram so as to make it possible to bring the punches into action alternately, automatic means being provided for so moving the carrier. In such machines the punches may be shaped to form a head upon the work, or to form a recess in the end of the work, and the operation is unusually carried out at room temperatures.

Hitherto in such machines the means for producing the transverse movement of the carrier has included a spring-loaded block sliding in a slot in an oscillating lever. In such mechanism the friction between the sliding block and the slot in the lever in the course of time produces wear, with the result that the machines have to be taken out of service from time to time for repair. Further in such mechanism the stresses applied to some of the working parts are bending stresses so that these parts have to be of robust and relatively heavy construction. In the construction in accordance with the present invention the stresses applied to the working parts are mainly in the form of tension or compression with the result that such parts can be of lighter construction than hitherto thus enabling the machine to be driven at a higher speed than is the case with existing constructions.

The object of the present invention is to provide improved automatic means for producing the transverse movement of the carrier.

According to the present invention the transverse movement of the carrier is produced by mechanism including a floating member which is moved by a pair of parallel links of equal length, the floating member being connected to the ram and to the carrier, or to carrier-actuating mechanism by further links, the parallel links being operable at any position of the ram to move the carrier from one end of its travel to the other. Such movement takes place during the periods when the punches are not in engagement with the work.

Further, the mechanism for producing the movement of the carrier may comprise a floating member to which are pivoted a pair of primary links and a pair of secondary links all operating in the same or parallel planes at right angles to the face of the body and parallel to the direction

2

of movement of the ram, the two primary links being of the same length and being parallel to each other, one of the primary links being pivotally connected to the carrier, or to carrier-actuating mechanism, and the other being pivoted to the ram, the two secondary links being of the same length and being parallel to each other and pivoted to the floating member at one pair of ends, and the other end of one of them being pivotally mounted at a fixed point and the other end of the secondary line being pivoted to a lever which is caused to oscillate about the said fixed point. With this arrangement the carrier can be moved from one position to the other at any position of the ram by turning the lever.

15 Stops may be provided on the head adapted to be engaged by a projecting lug on the carrier at each end of its movement.

The invention is illustrated in the accompanying drawings wherein:

20 Figure 1 is a section in side elevation of one type of heading machine embodying the present invention.

Figure 2 is a section on the line 2—2 in Figure 1.

25 Figure 3 is a view of the head of this type of machine showing a modification.

Figure 4 is a section in side elevation of another type of heading machine embodying the present invention.

30 Figure 5 is a section on the line 5—5 in Figure 4.

Figure 6 is a view showing the mechanism of Figure 4 in the other extreme position.

Figure 7 is a section on the line 7—7 in Figure 6.

35 In the constructions shown in Figures 1 to 3 the body, die, ram and head are constructed as usual, the body 10 having a die 11 with an opening 12 into which the stock is fed and the ram 13 being mounted in guides 14 for reciprocation by crank and pitman 15 from the shaft 16. The carrier is in the form of a slide 17 mounted for rectilinear reciprocating movement on the head 18 of the ram.

40 The operating mechanism for producing the reciprocating movement of the slide 17 incorporates a floating member 19 which may be formed as a metal plate, or may be fabricated, and which may be of approximately triangular shape as shown, although this is for convenience only, the actual shape of the plate being of no major importance as regards the working of the mechanism.

45 The head 18 of the ram is provided with a projecting lug 20 and the slide 17 is also provided with projecting lugs 21 and these lugs are con-

nected to the floating member 19 by a pair of spaced links 22 and 23, which are of the same length. In the construction of Figure 1 these links are pivotally connected at one pair of ends to the said lugs and at the other pair of ends to the floating member 19 and are parallel.

In the alternative construction shown in Figure 3 these two links, which are the primary links, are connected by a third link 24 pivotally connected between the ends of the primary links which are adjacent to the head and slide, and in this arrangement a third link 25 is pivoted at one end to the lug 21 on the slide and at the opposite end it is pivoted to the primary link 23.

In both constructions the floating member 19 is moved by a pair of secondary links 26 and 27 which are always parallel and are of the same length, and one of these links, namely 26, is pivoted to a fixed bracket 28 upon which is pivoted, about the same axis, a control lever 29 to which is also pivoted the other of these secondary links, namely 27. The control lever 29 is oscillated by providing its opposite end with a roller 30 which engages a rotating cam 31, the roller 30 being kept in contact with the periphery of the cam 31 by suitable spring means, such as spring 32 acting on the arm 33 fixed on the pivotal axis 34.

The cam is fixed upon a shaft 35 on which is fixed a gear wheel 36 meshing with a gear wheel 37 on the shaft 16, the ratio between these wheels being 2:1.

The operation of the mechanism is as follows: commencing from the position shown in Figure 1 the roller 30 travels the dwell portion 38 whilst the ram moves from right to left and the upper punch 39 engages the stock in the die 11. On the return stroke the rise portion 40 of cam 31 causes the link mechanism to move the punch slide 17 vertically so that the lower punch 41 is brought into line with the die for the next forward (right to left) stroke when the roller 30 travels the dwell portion 42. On the next return stroke the roller 30 travels the fall portion of cam 31 and the link mechanism returns the slide to its original position.

Limiting stops 43 are preferably provided on the head 18 to be engaged by a lug 44 on the slide 17 and there may also be positioning means, such as generally indicated at 45.

In the construction shown in Figures 4 to 7, the invention is shown applied to a heading machine of the type in which the punches are mounted in a carrier which is rotated about an axis parallel to the direction of reciprocating of the ram to bring the punches alternatively into the operative position. The arrangement of the body, die, ram and ram operating mechanism is the same as in the previous construction but in this construction the punch carrier 46, carrying the punches 47 and 48 is mounted on the end of a shaft 49 which can rotate in a bearing, generally shown at 50, in the ram and the head of the ram may be provided with limit stops as shown at 51 to be engaged by faces 52 on the carrier at the two extreme positions of its oscillatory movement. Also positioning means may be provided, as indicated generally at 53, 54.

The shaft 49 is oscillated from the link mechanism through any suitable gearing, that being shown comprising a shaft 55 journaled in a bearing 56 in the ram and having a bevel gear 57 which meshes with a bevel gear 58 on the end of the shaft 49. The link mechanism is similar to that shown in the previous construction and com-

prises a floating member 59 to which are connected the primary links 60, 61 and the secondary links 62, 63.

A lever 64 is fixed to the end of shaft 55 and the link 61 is pivotally connected to the end of said lever. The other link 60 is pivotally connected to the end of shaft 55. The mechanism is operated as before by a cam and the movement of the mechanism caused by the cam causes oscillation of the shaft 49 so as to bring the punches 47, 48, successively into the operative position for acting on the stock which is in the die. Figure 4 shows the mechanism in one extreme position at the beginning of a forward stroke of the ram and Figure 6 shows the mechanism in the other extreme position at the beginning of the next forward stroke, the shaft 49 having been turned to bring the other punch into the operative position.

In either construction the movement of the carrier in one direction may be produced by the action of spring means as shown or alternatively a cam may be used having a groove on its periphery or face for producing the movement in both directions. In a further alternative two cams may be used, one producing it in the reverse direction.

What I claim then is:

1. In a heading machine of the kind having a die through which stock is fed and a reciprocating ram having a head upon which is mounted a movable punch carrier carrying two spaced punches, the carrier being movable transversely to the direction of movement of the ram to bring the punches into action alternately; mechanism for moving the carrier transversely comprising, a member mounted for floating movement, a pair of primary links, parallel and of equal length, one connecting said floating member to the ram and one connecting said floating member to the punch carrier, a pair of secondary links, parallel and of equal length acting at one pair of ends on said member and operating means acting on the other pair of ends of said parallel links said operating means being driven in timed relationship with the reciprocation of the ram to cause periodic movement of the punch carrier from one end of its travel to the other.

2. In a heading machine of the kind having a die through which stock is fed and a reciprocating ram having a head upon which is mounted a movable punch carrier carrying two spaced punches, the carrier being movable transversely to the direction of movement of the ram to bring the punches into action alternately; mechanism for moving the carrier transversely comprising, a member mounted for floating movement, a pair of primary links and a pair of secondary links, said links being disposed in the same or parallel planes all parallel to the direction of movement of the ram, the two primary links being of equal length and parallel to each other and being pivotally connected at one pair of ends to said floating member, at the other end, one primary link being pivotally connected to the carrier and the other being pivotally connected to the ram, said two secondary links being of equal length and parallel to each other and pivotally connected to the floating member at one pair of ends, at the other end, one of said secondary links being pivotally mounted at a point fixed in relation to the fixed parts of the machine, an operating lever pivotally connected to the other secondary link at this other end and means for causing oscillation of said operating lever about

the axis of said fixed point in timed relationship with the reciprocation of the ram.

3. A heading machine according to claim 2 wherein the operating lever is moved by means of a rotatable cam which is driven in timed relationship with the reciprocation of the ram.

4. A heading machine according to claim 2 wherein the carrier is in the form of a slide mounted on the head of the ram for reciprocation thereon in a direction at right angles to the direction of movement of the ram, one of the primary links being pivotally connected to the head of the ram and the other being pivotally connected to the slide.

5. A heading machine according to claim 2 wherein the carrier is in the form of a slide mounted on the head of the ram for reciprocation thereon in a direction at right angles to the direction of movement of the ram, one of the primary links being pivotally connected at one end to the head of the ram, the other primary link being pivotally connected at one end to one end

5

of a link the other end of which is pivotally connected to the slide and a further link pivotally connected at its ends to the said ends of the primary links.

6. A heading machine according to claim 2 wherein the carrier is mounted on the end of a shaft which is rotatably mounted in or on the ram parallel to the direction of movement of the ram, said shaft being adapted to be oscillated by a further shaft carried by the ram one of said primary links being pivoted at one end on said further shaft and the other primary link being pivotally connected to one end of a lever the other end of which is fixed to said further shaft.
